SHELF UNIT FOR STORING BLUE PRINTS OR SIMILAR ARTICLES

Frank R. Sweet, Jr., 56 Fayerweather,
Cambridge, Mass. 02138

Filed Oct. 30, 1968, Ser. No. 14,226

Term of patent 14 years

Int. Cl. D6—01

U.S. Cl. D33—2

Fig. 1

Fig. 2

Fig. 3

Fig. 4

FIG. 1 is a perspective view of a shelf unit for storing blue prints or similar articles showing my new design:

FIG. 2 is a front elevation view of FIG. 1:

FIG. 3 is a side elevation view from either side of FIG. 1; and

FIG. 4 is a rear elevation view of FIG. 1.

I claim:

The ornamental design for a shelf unit for storing blue prints or similar articles, substantially as shown.
